F. M. JOSLIN

METHOD OF MAKING COLLAPSIBLE BOXES

Filed March 26, 1927

Patented Dec. 4, 1928.

1,694,126

UNITED STATES PATENT OFFICE.

FRANK M. JOSLIN, OF AMSTERDAM, NEW YORK.

METHOD OF MAKING COLLAPSIBLE BOXES.

Application filed March 26, 1927. Serial No. 178,591.

This invention relates to a method of making a collapsible box, and more particularly to a method of making a box for containing eggs.

5 One object of the invention is to provide a method of producing a box easily and economically from a single integral blank of material such as fiber board or the like.

A further object is to provide a process 10 resulting in the production of a box in a collapsed condition, thus obviating the troublesome and expensive operation of collapsing the box after it has been formed in order to get it into a flat condition for shipping 15 purposes.

A still further object is to provide a method in which the parts of the blank are folded into flat condition as the box is formed so that collapsing of the box after it 20 is made is rendered unnecessary.

Another object is the provision of a method of forming a collapsible box which can be readily set up or opened when it is desired to use the same.

25 A further object is to provide an improved method of making a box which can be carried out rapidly and efficiently by means of machinery and which requires practically no hand operation.

30 The invention is set forth in the following specification taken in connection with the accompanying drawings, forming a part thereof, it being understood, of course, that various changes and modifications within the 35 scope and spirit of the invention may be resorted to if desired.

In said drawings:

Fig. 1 is a plan view of one form of blank which may be employed in making the box;

40 Fig. 2 is a similar view showing the first steps in making the box; in this view the two opposite edge portions of the blank are folded inwardly over the body of the blank;

Fig. 3 illustrates a further step in which 45 the edge portion of the blank opposite the cover is folded inwardly over the other edge portions, it being understood that in the final folding operation the edge portion including the cover is folded down upon the other portions;

Fig. 4 is a perspective view of a completed box showing the same opened up after being formed; and

Fig. 5 is a plan view of a slightly modified form of blank in partially folded condition.

Referring to the drawings more in detail,

in producing a box according to the present invention a blank such as illustrated in Fig. 1 is employed, and which may be made of fiber board or any other suitable material. 60 This blank comprises a main or body portion B and a cover portion C. The portion B of the blank is provided with two substantially parallel score lines *a*, *a* which extend across the blank from adjacent the cover C 65 to the opposite side, and also with two substantially parallel score lines *b*, *b* arranged substantially at right angles to the lines *a*, *a*. The edge portions X, X of the blank outside of the lines *a*, *a* are of the proper and desired width to form two sides of the completed box. The edge portions Y, Y outside of the lines *b*, *b* similarly form the other two sides of the completed box. The corners G of the blank outside of the lines *a*, *a* and 70 *b*, *b*, form gussets each of which extends between two adjacent ends of the edge portions X, Y. Each of the gussets G is provided with a score line 10 which extends diagonally outwardly from the intersection of the 75 lines *a* and *b* and which bisects the gussets or divide the same into two substantially equal portions 11 and 12. These portions will hereinafter and throughout the claims be designated respectively as "inner" and 80 "outer" portions, that is, the inner portions will be understood as those portions 11 which border the folded sides X of the box and the outer portions will be understood as the 85 portions 12 which border the sides Y of the 90 box.

A score line 13 is provided between the cover-portion C and the edge portion Y and another similar line 14 extends transverse of the cover portion C adjacent the free end 95 thereof to form a flap C' on the end of the cover. It will be understood that the score lines *a*, *b*, 10, 11 and 12 are provided to facilitate folding of the blank along these lines. They constitute lines of fold. Scoring of 100 the blank may be dispensed with if a material is employed which would readily fold or bend along the lines where folding is desired.

In the form shown in Fig. 5, the only 105 modification is that the corners of the main body portion of the blank are left square instead of being beveled off. The result is that the gussets G' are somewhat larger and as a result the inner and outer portions 11' 110 and 12' thereof are greater in area than the corresponding portions 11 and 12 of the

other form. Also when such larger gussets are folded against the side portions X, the upper edges of the same lie substantially flush with the tops of said side portions instead of below the same as shown in Fig. 4.

From the foregoing it will be understood that in forming the box, the edge portions X, X are first folded inwardly and downwardly over the body of the blank. A suitable glue or adhesive of any kind is then applied to the inner portions 11 of the gussets, such adhesive being indicated by the stippling in Figs. 2 and 3. The edge portion Y opposite the cover C is then folded inwardly and downwardly over the portions X and finally the other edge portion Y, including the cover C, is folded inwardly and downwardly over the other portions. When the edge portions Y are folded as described, the gussets G are folded down upon the outer surfaces of the edge portions X, and since the inner portions 11 are supplied with adhesive, such portions will be secured to the outer surfaces of the portions X. It is, of course, obvious that instead of applying the adhesive to the inner portions 11 of the gussets it might be applied to the sections on the outer surfaces of the portions X against which the portions 11 are folded.

After the blank is folded as described, the box is completed. It is in flat or collapsed condition and therefore requires no further operation to prepare it for packing and shipment. When the box is to be used, it is only necessary to lift the portions X and Y into vertical position. This can be readily done since these portions are in effect hingedly connected to the bottom of the box. When the sides X and Y are lifted as described the gussets G take the position shown in Fig. 4. This is permitted by reason of the fact that the outer portions 12 of the gussets are hingedly connected to the inner portions 11 and also to the adjacent ends of the edge portions Y. By reason of the adhesion of the inner portions 11 of the gussets to the side portions X it will be evident that the sides of the finished box can not be turned outwardly beyond the position illustrated in Fig. 4, while at the same time the sides can be turned inwardly and the box collapsed whenever desired. When in use the inward collapsing of the sides X and Y is prevented by the usual partition strips employed in egg boxes or by the contents of the box itself. The cover C of the box is hingedly connected to the side Y and can be turned down to cover the box, the flap C' being inserted in the box to hold the cover in position.

Having thus described the invention, what is claimed as new and desired to be secured by Letters Patent is:

1. The process of producing from a single blank a collapsible box in collapsed condition named folded portions.

which consists in folding two opposite edge portions of the blank inwardly and downwardly over the body of the blank, folding the other two opposite edges of the blank inwardly and downwardly upon said first 70 named folded portions, the corners of said blank between the lines of fold forming gussets which are folded down upon said first named folded portions during said second folding operations, and adhesively securing 75 the inner portion only of each of said folded gussets to the adjacent outer surface of said first named folded portions.

2. The process of producing from a single blank a collapsible box in collapsed condition 80 which consists in folding two opposite edge portions of the blank inwardly along substantially parallel lines *a* and down over the body of the blank, folding the two opposite edge portions of the blank along substantially parallel lines *b* and down upon said first named folded portions, the corners of the blank between said lines *a* and *b* forming gussets G which are folded down upon the surface of said first named portions during 90 said second folding operation, and securing the inner portion only of each of said gussets to the outer surface of the said first named portion against which it is folded.

3. The process of producing from a single blank a collapsible box in collapsed condition which consists in folding two opposite edge portion of the blank inwardly and downwardly upon the body of the blank, applying adhesive to a limited area on the outer surface of said folded portions adjacent each end thereof, folding the other opposite edge portions of said blank inwardly and downwardly upon said first named folded portions, the corners of the blank between said lines of fold forming gussets between said folded portions which gussets are folded down upon said first named folded portions during said second folding operation, said adhesive being so placed as to secure the inner portion of each of said gussets to the adjacent outer surface of the first named folded portions.

4. The process of producing from a single blank a collapsible box in collapsed condition 115 which consists in folding two opposite edge portions of the blank inwardly and downwardly over the body of the blank, folding the other two opposite edges of the blank 120 inwardly and downwardly upon said first named folded portions, the corners of said blank between the lines of fold forming gussets which are folded down upon said first named folded portions during said second folding operations, applying adhesive to the inner portion of each of said gussets before 125 said second folding operation, whereby said inner portions of the gussets are secured to the adjacent outer surfaces of said first

5. The process of producing from a single blank a collapsible box and cover in collapsed condition which consists in providing a blank having a cover forming portion extending from one edge thereof, folding two opposite edge portions of the blank inwardly and downwardly over the body of the blank, folding the edge portion of the blank opposite said cover forming portion inwardly and downwardly upon said first named folded portions, folding the remaining edge of the blank including said cover forming portion inwardly and downwardly upon said first named folded portions, the corners 10 of said blank forming gussets between said first named and second named folded portions which gussets are folded down upon said first named portions during said second and third folding operations, and adhesively 15 securing the inner portion of each of said gussets to the adjacent outer surface of said first named folded portions.
6. The process of producing from a single blank a collapsible box and cover in collapsed condition which consists in providing a blank having a cover forming portion ex- 20 tending from one edge thereof, scoring said blank along two substantially parallel lines extending across the blank from adjacent said cover forming portion to the opposite 25 edge of the blank, scoring said blank along two other lines substantially at right angles to the first named lines, the corners of the blank between said first and second named lines forming gussets, bisecting each of said 30 gussets by a score line extending diagonally outwardly from the intersection of said first and second named lines, folding the opposite edges of said blank inwardly and downwardly along said first named lines, applying 35 adhesive to the inner portion of each of said gussets beyond said bisecting lines, folding the other two edges of said blank including said cover portion inwardly and downwardly along said second named lines and into contact with said first named folded portions, 40 whereby the inner portions of said gussets are secured to the outer surfaces of said first named folded portions.
- In testimony whereof I hereunto affix my 45 signature.

FRANK M. JOSLIN.
